UNITED STATES PATENT OFFICE.

GEORGE MARSHALL SMITH, OF CHICAGO, ILLINOIS, ASSIGNOR TO INTERSTATE IRON AND STEEL COMPANY, OF CHICAGO, ILLINOIS, A CORPORATION OF ILLINOIS.

COOLING BED.

Application filed October 22, 1921. Serial No. 509,682.

To all whom it may concern:

Be it known that I, GEORGE MARSHALL SMITH, a citizen of the United States, residing at Chicago, in the county of Cook, State of Illinois, having invented certain new and useful Improvements in Cooling Beds, do hereby declare that the following is a full, clear, and exact description of the same.

My invention relates to cooling beds used in handling hot metal bars as they are delivered from the reducing-rolls of a rolling-mill and consists in the novel and useful constructions herein described and then pointed out in the appended claims.

In the accompanying drawings, which illustrate a practical embodiment of the features of my invention and in which the same reference numerals indicate similar parts in the different views, Fig. 1 is a top plan view 15 of a longitudinal section or portion of a cooling bed equipped with my invention, the metal bars under treatment being shown broken-away for convenience of illustration; Fig. 2 is a sectional view on the line 2—2 in 20 Fig. 1; Figs. 3 and 4 are detail sectional views on the lines 3—3 and 4—4 respectively in Fig. 1, and Fig. 5 is a diagrammatic view 25 to show certain arrangements of parts.

The objects of my invention are to provide certain improvements in cooling beds for metal bars whereby the bars as they are moved down the inclined metallic skids are subjected to minimum contact therewith to reduce their chilling and enable their surfaces that have been in temporary contact with the skids to be restored to the same temperature as the adjacent metal of the bar by the conduction of the heat from the hotter to the chilled colder part of the bar, and also whereby the bottom bar of a pack on the stationary rack-section of the bed is subjected to minimum contact with the metallic troughs or pockets to allow the heat from the bars in the center of the pack to anneal 40 it. Obviously the term bar as used herein includes all such shapes as rods and other forms of metal which are usually long in proportion to their width or thickness.

Referring to the accompanying drawings 45 which show the features of my invention applied to a cooling bed of well-known construction, the reference letter A designates a run-out table comprising a long trough provided with a series of positively-driven

cone-shaped feed-rolls A', the peripheries of 55 which project through openings into the trough and serve to convey the metal bar as it is delivered from the reducing-rolls. It is to be understood that the trough is usually long enough to accommodate a 300 60 foot bar, and that the cooling bed, of whose length only a section is shown, is correspondingly extended.

The inclined bed B constitutes the escape- 65 ment skid-section of the cooling apparatus, upon which the bars *x* are cooled preparatory to their being cut into suitable lengths, and consists of a series of rigid inclined skid beams B' upon which the bars are delivered from the trough. Each skid beam is provided with a series of vertical ribs or flanges B², B³, B⁴, B⁵, B⁶, and B⁷, arranged longitudinally on its upper face in staggered relation; preferably the disposition of these flanges is such that alternate flanges are not 70 in alignment lengthwise of the beam, for example as shown in Figs. 1 and 3. These flanges are narrow and project sufficiently above the beams to form skids or ways that hold the bars out of contact with the beams. 75 Between the beams B' are journaled in the bed a series of rocking-shafts C parallel with the beams and having radial arms C', C² and C³ extending therefrom. The arms C' on the ends of the shafts are arranged 80 to pass through open-end slots *a* in the trough A so that upon oscillation of the shafts they will transfer the bar out of the trough to the bed. The arms C² on each shaft are arranged in a plane at right angles with 85 the plane of the arms C³ upon the same shaft, and each series of arms is also arranged in a straight horizontal row extending lengthwise of the bed so that the hot metal bars will be preserved in straight lines. Suitable mech- 90 anism which is well known and forms no part of my present invention, and so need not be here shown and described, actuates the rocking-shafts so that they are simulta- 95 neously rocked back and forth one-quarter of a revolution at each movement of the reciprocating mechanism, carrying the series of radial arms C² and the series of radial arms C³ alternately into a vertical position with 100 their ends projecting a short distance above the inclined beams B', as represented by the arms C² in Fig. 2, so that the arms which extend in a vertical position will form a

row of dogs arranged in a straight horizontal line in order to hold the bars from sliding down the inclined ways. The horizontal rows of the arms C^2 alternate with the rows 5 of arms C^3 , so that the rocking motion of the shafts allows the bars lying on the skids to move by gravity successively down the inclined skids from one row of flanges to the next lower row until they fall one by one 10 from the last row of flanges B' upon the inclined guides B^3 at the lower end of the skid-section of the bed B by which they are delivered to the initial row of pockets of the rack-section of the cooling bed.

15 The rack-section of the cooling bed is composed of a series of parallel stationary racks D arranged respectively in line with the series of skid-beams as shown in Fig. 1. Each rack is provided with a series of troughs 20 or pockets D' which are V-shaped in cross-section, each series of pockets being arranged in a straight row lengthwise of the bed to preserve the hot bars in straight lines. Suitable mechanism of any known construction 25 may be employed to lift the bars from each pocket and deposit them in the next one, and when the bars are to be arranged in packs x' in the pockets suitable mechanism of known construction may be employed to 30 deliver the bars from the skid-section of the bed to the first row of pockets in the rack-section so that they will be disposed therein in a pack as shown; mechanisms for both purposes are now well-known and need not 35 be here described, and devices for feeding the bars forward upon the racks from one line of pockets to another are generally designated at D^2 . Each of the first three pockets in each rack is provided with a vertical flange D^3 on each of its inclined faces, 40 and the flanges of each rack are arranged in staggered relation along its length, and preferably the disposition of these flanges is such that neither flange of any pocket is 45 in line with a flange of an adjacent pocket, as shown in Fig. 5. Also, preferably the racks are wider than the skid-beams and the flanges of each beam and its aligned rack are staggered along the longitudinal line of 50 each such couple, as shown in Fig. 2.

In cooling beds as heretofore constructed, so far as I am aware, the bars while on the skid-beams rested on the flat surface thereof which provided a bearing several inches wide 55 and as the same portions of the hot bars were in contact with the cold beams during the entire period of their travel down the inclined section of the bed these portions became chilled. Also, as the racks of such previous beds were formed with their bar-supporting surfaces of approximately the same 60 width as the skid-surfaces of their beams, and as these surfaces of both sections of the bed were in alinement, the chilled portions 65 of the hot bars were further chilled below

the temperature of the adjoining metal in the bars while they rested on the racks; and, furthermore, the face of the bottom bar and edges of the several bars in a pack on the racks were cooled so fast by the colder metal 70 of the racks drawing heat from them faster than they could absorb heat from the pack that the heat from the center bars of the pack was not sufficient to evenly anneal them. The general theory of annealing packs of hot bars, as for example where the bars are intended for use in making vehicle springs or other parts requiring a standard of hardness, is that the heat from the center of the pack will anneal its surfaces, and in the use 75 of previous machines such as just described the effect of the racks was to prevent the contacting portions of the bottom bars of the packs from annealing to the same degree of hardness as the rest of the bar. The critical temperature for properly annealing spring bars is reached by the time the bar is ejected from the third pocket in the rack-section, and in the prior apparatus the chilled 80 portions of the bars were below this temperature at this point so that the bars when finished were not uniform and did not meet the Brinell test which is the standard requirement of vehicle spring manufacturers. 85

By my invention I obviate both of these defects. The bars while passing down the inclined section of the bed rest on the narrow flanges, and as these flanges on each beam are staggered in the line of travel of the bar along the beam the portions of the bar contacting with the skid are changed as the bar moves down it. This enables each small portion of the bar that has been in contact with the skid and so momentarily chilled to be reheated to the temperature of 90 the other parts of the bar by the exchange of heat by conduction from the non-chilled to the chilled portion. The portion chilled by contact with any one of the flanges on the beam is so small and the contact is so momentary that the heat conduction from both sides of it restores its temperature to that of the rest of the bar while another portion is in contact with the succeeding flange, and the end flange B' is so arranged that the 95 portion of the bar in contact with it is remote from any immediately preceding chilled portion so that the latter will be reheated by conduction while the bar is passing along the final flange. The narrow flanges 100 of the racks likewise prevent the chilling of the bottom bar and the edges of the bars forming the pack to any appreciable extent, and allow these surfaces to absorb heat from the pack to approximately the same degree; they decrease the extent of the hot surfaces exposed to the cold metal of the racks 105 and allow the bars in the center of the pack to anneal the others. The bars are carried 110 across the bed with a minimum of chilling 115

until they reach the pocket where they are below the critical temperature; in practice all the bars are finished below the Brinell test.

5 I claim:

1. In a cooling bed for metal bars, the combination of a series of inclined skid-beams provided with skid-flanges on their upper faces, the flanges on each beam being 10 arranged longitudinally in staggered relation, and means to feed the bars successively along the flanges lengthwise of the beams.

2. In a cooling bed for metal bars, the combination of a series of inclined skid-beams provided with skid-flanges on their upper faces arranged in horizontal rows lengthwise of the bed, the flanges on each beam being staggered in different planes lengthwise thereof, and means to feed the 20 bars along the beams whereby they are successively carried by the horizontal rows of flanges.

3. In a cooling bed for metal bars, the combination of a series of racks each provided with a series of pockets, flanges on 25 certain of the pockets of each rack arranged in staggered relation to each other, and

means to move the bars along the racks from one pocket to an adjoining one.

4. In a cooling bed for metal bars, the 30 combination of a series of racks each provided with a series of pockets, a plurality of pockets at the receiving end of each rack having flanges arranged in staggered relation to each other, and means to move the 35 bars along the racks from one pocket to an adjoining one.

5. In a cooling bed for metal bars, the combination of a series of inclined skid-beams forming the first section of the bed 40 provided with skid-flanges on their upper faces, the flanges on each beam being staggered in different planes lengthwise thereof, means to feed the bars along the flanges, a series of racks forming the second section 45 of the bed and provided with a series of pockets, flanges on a plurality of the pockets at the receiving end of each rack arranged in staggered relation in each pocket, and means to move the bars along the racks 50 from one pocket to an adjoining one.

In testimony whereof I affix my signature.

GEORGE MARSHALL SMITH.
